UNITED STATES PATENT OFFICE.

EDOUARD DU BOIS MATHEY, OF CRANFORD, NEW JERSEY, AND AUDLEY OSCAR WILLIAMS, OF BREWSTER, FLORIDA, ASSIGNEES TO AMERICAN CYANAMID COMPANY, OF NEW YORK, N. Y., A CORPORATION OF MAINE.

PHOSPHORIC-ACID RECOVERY.

No Drawing.

Application filed September 6, 1923. Serial No. 661,311.

This invention relates to a method of producing phosphoric acid in cases in which either the element itself or one of its volatile compounds, is liberated and expelled from a 5 highly heated charge. It refers more particularly to treatments of a nature carried out in a shaft furnace employing electrodes to heat the mass.

In the present embodiment of the invention, 10 the preliminary heating is effected by the combustion of fuel, elemental phosphorus, etc. in the shaft of the furnace, and the final or reaction temperature is attained by electrical means in the furnace pot. The electric 15 furnace is of the arc type and has a vertical charging shaft. The present invention refers particularly to a new method of increasing the pliability and obtaining a regulated flow of the charge in the vertical shaft, and 20 at the same time affording an easy method of escape for the upward moving gases. It thus refers to a process of increasing the porosity and permeability of the charge in the shaft, and at the same time retarding its downward 25 movement.

The object of this invention is to so regulate the feeding in the shaft of the furnace that the materials themselves will not block and clog the passage, and on the other hand will 30 not enter the pot too precipitously. With these and other objects in view the invention consists in the various steps and combination of steps constituting the process, and in the employment of a new material capable of 35 bringing about simultaneously two or more improved results, all as will be more fully hereinafter described and particularly pointed out in the claims.

As an example of the process, 1000 parts of 40 phosphate rock, 400 parts of silica, 50 parts of coke and 300 parts by weight of wood are taken to compose the charge. The material is fed into the shaft in the furnace through the charging device, and as it descends it meets 45 the upward rising gases, which are burned in contact with the charge by the introduction of air in the lower part of the shaft. After their escape from the furnace the gases carrying the phosphoric anhydride are treated in 50 any of the various methods found suitable for the collection of the phosphoric acid. Among these may be mentioned the absorption in towers, or the electrical precipitation by

means of the Cottrell process. At the bottom of the shaft is the pot of the furnace in which 55 the electrodes are located, requisite temperature is attained, and the phosphorus is liberated from the molten mass. When all the phosphorus is expelled the slag is discharged, from the furnace. It has been found advisable to maintain the reaction by an almost 60 continuous withdrawal of the residual slag.

Before entering the furnace the charge material may be treated in various ways. The rock, and silica may receive a preliminary sintering to avoid shaft choking, which is very 65 common where fine powders are used. In this case the sintered material and the wood are introduced into the furnace. Another and more improved method consists in introducing the silica in the form of sandstone, and dispensing with the preliminary clinkering. 70 This is a very economical method. It does away with the necessity of a preliminary sintering action, lessens the amount of fuel required 75 and very materially cuts down the labor costs.

The amount of wood added as compared with other fuels, such as coke, coal, etc. may be varied at will, and in fact wood alone may 80 replace all other fuels if so desired.

In the present invention the addition of wood is an extremely important feature and this whether added in small or large blocks, 85 plays a fourfold part in the process. A difficulty that is always met with in operating shaft furnaces, whether of the ordinary or the electrode type, is the proper feeding of the charge through the shaft. There is always a tendency to either choke or to precipitate the 90 fresh material into the reaction zone at a too rapid rate, or for the mass to block in the shaft and arch over. In the case of electric shaft furnaces the difficulties resulting from an improper feeding of the charge, are much 95 greater than in an ordinary shaft furnace, because a sudden accumulation of fresh material between the electrodes will cut off the arc.

When the wood added is of a size that will 100 properly bolster up the mass above it and through wedging, support the weight until the strength of the wood is lost by carbonization, the downward movement is regulated and the vertical column of fresh material does not bear too heavily upon the molten mass in 105 the bath. Another important feature consists

in the opening up of gas passages by shrinkage of the wood in changing to charcoal. In converting the phosphorus vapor into phosphoric anhydride, air is injected into the shaft just above the molten mass, and this aids in the shrinkage of the carbonized wood.

When the carbonized wood finally reaches the molten bath it is usually reduced to the condition of small chunks, and owing to the remarkable chemical activity of charcoal, it is more efficient in the reduction of phosphorus compounds than any other form of carbon. As the relative proportion of wood to other reducing agents such as coke, coal, etc., may be varied at will, it is possible to obtain almost any desired condition of the charging mass.

Although originally processes were suggested in which the charge consisted exclusively of phosphate rock and sand, these methods were later abandoned owing to the imperfect volatilization of the phosphoric anhydride, and the length of time required to effect the reaction. Theoretically phosphoric anhydride should be liberated on fusion with silica, but in practise it is found that complex side reactions are set up, which hold back the phosphoric anhydride, and in addition the viscosity of the molten charge hinders the liberation of the volatile anhydride. If now a sufficient amount of a reducing agent is added the phosphorus compounds will all be reduced to elemental phosphorus, which in vapor form is easily expelled from the bath. This reduction entails the use of a very considerable amount of reducing agent, usually in the form of wood and charcoal coke or fine coal, and as the phosphorus must be completely oxidized before it is collected, it is desired to recover as large a proportion of the energy supplied in the reducing agent as is possible. Consequently the gases are brought into intimate contact with the incoming charge, and air introduced, and the gases burned in contact with the charge. Theoretically the oxidation of the phosphorus should furnish to the incoming charge all the heat expended in reducing the phosphorus compounds, but the various side reactions and radiations make this impossible. To overcome as far as possible the loss consequent upon the oxidation and burning away of the wood by the injected air, the latter is regulated so that the combustion and the flame area is maintained close to the bath, and seldom reaches far up in the shaft. The gaseous products of combustion thus pass through the maximum length of charge in the shaft, and finally come in contact with the cold charge immediately after its introduction. This conserves the heat to the greatest degree possible.

Among the many advantages in the employment of wood as a regulating and reducing means, are its ready availability and relatively small cost in regions where extensive

water-powers exist, and the fact that all shapes, sizes, and varieties may be used.

It is obvious that those skilled in the art may vary the details of the process, and the nature of the product without departing from the spirit of the invention, and therefore we do not wish to be limited to the above disclosures except as may be required by the claims.

We claim:

1. A method of manufacturing phosphoric acid which comprises heating in an electric furnace an inorganic material capable of liberating phosphorus at elevated temperatures in the presence of sticks of carbonized wood, substantially as described.

2. A method of manufacturing phosphoric acid which comprises heating in an electric furnace a material capable of liberating phosphorus by means of reducing agents other than wood, and sticks of wood, and oxidizing the expelled phosphorus, substantially as described.

3. A method of manufacturing phosphoric acid which comprises heating in an electric furnace of the shaft type, a mixture of phosphate rock and sand, mixed with sticks of wood, and so regulating the feeding of the bath that the wood will be carbonized by the heat generated in the furnace pot, in addition to that resulting from the combustion of the escaping gases, and oxidizing the volatilized phosphorus, substantially as described.

4. A method of manufacturing phosphoric acid which comprises heating in an electric furnace of the shaft type, a clinkered mass of phosphate rock, sand and coke, mixed with sticks of wood, and so regulating the feeding of the bath that the wood will be carbonized by the heat generated in the furnace in addition to that resulting from the combustion of the escaping gases; and oxidizing the volatilized phosphorus, substantially as described.

5. A method of manufacturing phosphoric acid which comprises heating in an electric furnace phosphate rock, sand and chunks of wood, and so regulating the descent of the charge into the molten bath that the wood will become carbonized before entering the molten bath, and oxidizing the expelled phosphorus; substantially as described.

6. A method of manufacturing phosphoric acid which comprises heating in an electric furnace of the shaft type, a mass of material capable in presence of a reducing agent of expelling phosphorus at elevated temperatures, accompanied by blocks of wood, and so regulating the combustion of the rising gases through the introduction of air, that the wood will be slowly and progressively carbonized, and in shrinking will aid the escape of the rising gases, and the

downward movement of the charge, and oxidizing the liberated phosphorus, substantially as described.

7. A step in the method of manufacturing phosphoric acid which comprises charging an electric shaft furnace with a mixture of phosphate rock, sand, and coke, in the form of clinker, accompanied by blocks of wood in size sufficient to support and retard the downward movement of the charge in the shaft, and on charring allow the upward rising gases to penetrate the mass, and the charge itself to slowly be released, substantially as described.
10. In a method of manufacture of phosphoric acid from phosphate rock and silicious material in an electric furnace, the step which comprises adding to the charge a substance capable of equalizing the downward movement of the charge in the stack, increasing the permeability of the charge to the upward movement of the escaping gases, and capable in the molten bath of reducing compounds of phosphorus to the elemental state; substantially as described.
15. 8. In a method of manufacture of phosphoric acid from phosphate rock and silicious material in an electric furnace, the step which comprises adding to the charge a substance capable of decomposing and forming
20. 9. In a method of manufacture of phosphoric acid from phosphate rock and silicious material in an electric furnace, the step which comprises adding to the charge a substance capable of decomposing and forming
25. 10. In a method of manufacture of phosphoric acid from phosphate rock and silicious material in an electric furnace, the step which comprises adding to the charge a substance capable of decomposing and forming

charcoal at low temperatures, and shrinking during the decomposition, substantially as described.

10. In a method of manufacture of phosphoric acid from phosphate rock and silicious material in an electric shaft furnace, the step which comprises adding to the charge a substance capable of impeding the downward movement of the charge in the shaft, before decomposition, and later aiding the downward movement of the charge during decomposition, and finally aiding the liberation of the phosphorus in the molten bath, substantially as described.

11. A method of manufacturing phosphoric acid which comprises mixing wood with a mass capable of liberating phosphorus at elevated temperatures, heating the mixture, and oxidizing the liberated phosphorus.

12. A method of manufacturing phosphoric acid which comprises mixing sticks of wood with a clinkered mass of phosphate rock and silicia, heating the mixture in an electric furnace, and oxidizing the escaping phosphorus.

In testimony whereof we affix our signatures.
